SEAT ATTACHMENT

Elwin M. Kinney, Atlanta, Ga.

Application March 28, 1949, Serial No. 83,941

5 Claims. (Cl. 155—133)

1

This invention relates to a seat attachment, and more particularly to an attachment which can be conveniently secured to a seat to render it convertible from a non-cushioned seat to a cushioned seat and vice versa.

My seat attachment finds particular use in connection with the seats customarily found in ball parks and like places, and is designed to provide an individual cushion to be used at the pleasure of the patrons, especially the grandstand patrons, instead of the hard board seat afforded by the usual structures.

It has heretofore been the common practice to provide the patrons of an amusement park, such as a ball park, with individual cushions which are supplied at a small remuneration in addition to the price of admission. Such cushions have heretofore been entirely free from attachment or unattached to the permanent seats, and the cushions often become scattered and misplaced, and are often thrown away by overly enthusiastic patrons, thereby annoying and endangering other patrons and exhibitors.

An object of my invention is to provide a seat attachment in the nature of a cushioned seat which may be folded out of the way against the back of the seat structure when not in use.

Another object of my invention is to provide a seat attachment which is capable of being used as a cushioned seat when desired, and which may be folded up out of the way so as not to affect the height of the permanent seat above the floor when said attachment is in its inoperative position.

Another object of my invention is to provide a seat attachment of the type described which can be easily and conveniently attached to the customary grandstand seats in ball parks with but little or no alteration of the permanent seat structure.

Another object of my invention is to provide a seat attachment of the type described which is attached to the permanent seat structure by means preventing detachment therefrom when locked in inoperative position.

Another object of my invention is to provide a seat attachment of the type described which is simple in construction, economical to manufacture, efficient in operation and durable in use.

Other and further objects and advantages of my invention will be apparent from the following description taken in connection with the accompanying drawings in which like characters of reference designate corresponding parts throughout the several views, and wherein:

2

Fig. 1 is a side view of a seat showing my attachment in place thereon.

Fig. 2 is a front elevation of the device shown in Fig. 1.

Fig. 3 is a rear elevation of the device shown in Fig. 1.

Fig. 4 is a top view of a detail.

In the embodiment chosen for illustration, a typical grandstand type seat is shown having upright side frame members 10, 10', a plurality of cross frame members 11 forming a back rest, and a plurality of slats 12 forming a bottom or seat. My novel seat attachment comprises a cushion 13 which may be formed of sponge rubber or other suitable resilient material and which is carried by a base plate 14 to which it is secured by cementing or fastening in any suitable manner. The base 14 is attached along its rear edge to a pivot rod 15, the ends of which project beyond the sides of the base plate 14 and are pivotally mounted near the lower end of the fastening members 16, 16', in the angle formed where the back of the seat meets the permanent seat structure.

25 The fastening members 16, 16' are angle straps of metal or other suitable material having upstanding sides 17, 17' in which the ends of the pivot rod 15 are mounted, and bottom portions 18, 18' which are screwed or otherwise suitably fastened to the back cross frame members 11, the spacing apart of the fastening members being just slightly greater than the width of the cushion 13 and the base plate 14, so that when the attachment is folded up against the back of the chair or grandstand type seat, the screws 19 or other suitable fastening means in the bottom portions 18 of the fastening members 16, 16' are not accessible, and removal of my attachment is not possible until the base plate 14 and the cushion 13 are swung downwardly about the pivot rod 15 so as to uncover the fastening members.

When my seat attachment is lowered into operative position, the base plate 14 rests upon the slats 12 and the resilient cushion 13 is presented for use. When use of the cushion is not desired, the front of the base plate is raised to pivot the base plate about the rod 15 and to fold the cushion 13 against the cross frame members 11 forming the back of the permanent seat structure. In this position the U-shaped catch mounted on the front of the base plate, and which may extend slightly above the resilient cushion 13, will project between adjacent cross frame members 11 and engage the locking device 55 20 which is of ordinary construction having a

slot 21 to receive a coin or check and a handle 22 for manually releasing the lock after a proper coin or check has been inserted in the slot for the use of the cushion.

Although the usual grandstand seat is hard and uncomfortable because it is not form fitting, the height of the seat above the floor is usually engineered with accuracy, and it is important that this distance above the floor be not changed as long as the seat remains uncushioned. My seat attachment accomplishes this by folding away against the back of the permanent seat when the cushion is not desired. The smooth unobstructed under side of the base plate 14 forms a desirable back rest for the occupant of the seat when the cushion is not in use; and, also, in this position the cushion is protected from the weather but gets ventilation between the back cross frame members 11, as seen in Fig. 4.

It will also be noticed that my novel seat attachment does not interfere with the customary upward folding of the permanent seat structure, which, in the style shown in the drawing is designed to pivot about the pins 23, 23'.

It will be obvious to those skilled in the art that many modifications and changes can be made in the embodiment shown and described without departing from the scope of my invention as defined in the appended claims.

I claim:

1. In combination with a seat having a back rest and a bottom, a resilient cushion arranged selectively to be supported upon said bottom or to be folded against said back rest, supporting means beneath said cushion and to which said cushion is fastened, said supporting means being pivotally mounted in a fastening member secured to said back rest, a locking device mounted upon said back rest, a catch secured to said supporting means, said locking device being arranged to receive said catch when said resilient cushion is folded against said back rest, and means for releasing said catch from said locking means when it is desired to lower said cushion to be supported upon said seat bottom.

2. In combination with a seat having a back rest and a bottom, a resilient cushion arranged selectively to be supported upon said bottom or to be folded against said back rest, a base plate beneath said cushion and to which said cushion is fastened, said base plate being pivotally mounted in a fastening member secured to said back rest, a locking device mounted upon said back rest, a catch secured to said base plate, said locking device being arranged to receive said catch when said resilient cushion is folded against said back rest, and means for releasing said catch from said locking means when it is desired to lower said cushion to be supported upon said seat bottom.

3. In combination with a seat having a back

rest and a bottom, a resilient cushion arranged selectively to be supported upon said bottom or to be folded against said back rest, a base plate beneath said cushion and to which said cushion is fastened, said base plate being pivotally mounted in fastening members secured to said back rest, a locking device mounted upon the rear of said back rest, a catch secured to the front of said base plate, said locking device being arranged to receive said catch when said resilient cushion is folded against said back rest, and means for releasing said catch from said locking means when it is desired to lower said cushion to be supported upon said seat bottom.

4. In combination with a seat having a back rest and a bottom, a resilient cushion arranged selectively to be supported upon said bottom or to be folded against said back rest, a base plate beneath said cushion and to which said cushion is fastened, a pivot rod attached to said base plate along the rear edge of said plate, said rod being mounted in fastening members secured to said back rest, a coin controlled locking device mounted upon the rear of said back rest, a catch secured to the front of said base plate and projecting above said cushion, said locking device being arranged to receive said catch when said resilient cushion is folded against said back rest, and means for releasing said catch from said locking means when it is desired to lower said cushion to be supported upon said seat bottom.

5. In combination with a seat having a back rest and a bottom, a resilient cushion arranged selectively to be supported upon said bottom or to be folded against said back rest, a base plate beneath said cushion and to which said cushion is fastened, a pivot rod attached to said base plate along the rear edge of said plate and having its ends projecting beyond the sides of said base plate, said ends being mounted in fastening members secured to said back rest, a coin controlled locking device mounted upon the rear of said back rest, a catch secured to the front of said base plate and projecting above said cushion, said locking device being arranged to receive said catch when said resilient cushion is folded against said back rest, and means for releasing said catch from said locking means when it is desired to lower said cushion to be supported upon said seat bottom.
